UNITED STATES PATENT OFFICE.

JOHN F. CARLI, OF REDWOOD CITY, CALIFORNIA.

DESIGN FOR A TRAFFIC SIGNAL.

Application filed November 27, 1923. Serial No. 7,896. Term of patent 7 years.

To all whom it may concern:

Be it known that I, JOHN F. CARLI, a citizen of the United States, residing at Redwood City, in the county of San Mateo and State of California, have invented a new, original, and ornamental Design for a Traffic Signal, of which the following is a specification, reference being had to the accompanying drawing, forming part thereof.

Fig. 1 is a front elevation and Fig. 2 is a top plan view of a traffic signal showing my new design.

I claim:

The ornamental design for a traffic signal, as shown.

JOHN F. CARLI.
